CLAIM

The ornamental design for a telephone protector block, as shown and described.

DESCRIPTION

FIG. 1 is a front elevational view of a telephone protector block showing my new design;

FIG. 2 is a bottom plan view thereof;

FIG. 3 is a rear elevational view thereof;

FIG. 4 is a top plan view thereof;

FIG. 5 is a side elevational view thereof;

FIG. 6 is a side elevational view thereof, showing the side opposite that seen in FIG. 5; and

FIG. 7 is a horizontal sectional view thereof as seen from the plane 7—7 in FIG. 1.

FIG. 1.

FIG. 2.

FIG. 3.

FIG. 4.

FIG. 5.

FIG. 6.

FIG. 7.
